UNITED STATES PATENT OFFICE

145,256

DESIGN FOR A CLOTHESLINE CLAMP

Richard L. Odiorne, Yellow Springs, and John S. Monroe, Springfield, Ohio

Application November 7, 1945, Serial No. 123,947

Term of patent 14 years

(Cl. D17—6)

To all whom it may concern:

Be it known that we, Richard L. Odiorne and John S. Monroe, both citizens of the United States, residing respectively at Yellow Springs, in the county of Greene and State of Ohio, and at Springfield, in the county of Clark and State of Ohio, have invented a new, original, and ornamental Design for a Clothes Line Clamp, of which the following is a specification, reference being had to the accompanying drawing, forming a part thereof.

In the drawing,

We claim:

The ornamental design for a clothes line clamp, as shown.

RICHARD L. ODIORNE.
JOHN S. MONROE.
